UNITED STATES PATENT OFFICE

OSCAR RITTERBUSCH, OF CHICAGO, ILLINOIS

LOCK

Application filed July 15, 1931. Serial No. 551,025.

The invention relates to locks and is particularly adapted to be embodied in the doors of a dwelling place or the like.

A particular object of the invention is to provide an improved lock which will hold a door in its locked position in such manner that the door cannot rattle.

One form of the invention is embodied in a lock which comprises a wedge member carried by the door and adapted to engage a pivoted member carried by the door frame, the construction being such that when the door is in its locked position, the wedge member gravitates down into a position wherein it firmly engages the pivoted member and holds the door against any movement relative to the door frame. Any force tending to cause some movement between the door and its frame will cause the wedge to gravitate a slight distance downwards so that it will wedge itself deeper into the pivoted member.

Other objects and advantages will become apparent as the following description progresses, reference being had to the accompanying drawings, wherein:

Figure 1 is a section taken on line 1—1 of Fig. 2, the view being taken from the inside of a door which is provided with a lock embodying the invention.

Fig. 2 is a section taken on line 2—2 of Fig. 1.

Fig. 3 is a section taken on line 3—3 of Fig. 1.

Fig. 4 is a section taken on line 4—4 of Fig. 1.

Fig. 5 is a section taken on line 5—5 of Fig. 1.

Fig. 6 is a perspective view of certain members which form parts of the improved lock.

Fig. 7 is a section taken on line 7—7 of Fig. 1.

Fig. 8 is a section taken on the same line as Fig. 7, but showing the door in a partly opened position.

Fig. 9 is a view resembling Fig. 1, but showing another form of the invention embodied in a lock.

Fig. 10 is a section taken on line 10—10 of Fig. 9.

Fig. 11 is a view similar to Fig. 1, but showing a lock which embodies another form of the invention, and

Fig. 12 is a section taken on line 12—12 of Fig. 11.

Referring for the present to Figures 1 to 8 inclusive, wherein a preferred embodiment of the invention is illustrated, the reference character 10 designates a door which is mounted in a door frame 11 by hinges (not shown). The door 10 is equipped with the improved lock which is designated generally by the reference character 12.

The improved lock 12 comprises a keeper 15 which is pivoted by a pin 16 in a housing member 17, the member being fixed in a recess 18 provided in the door frame 11. A spring 19 wound around a pin 20 tends to rotate the keeper 15 in a clockwise direction (Fig. 2) so that the keeper 15 will occupy the position wherein it is shown in Figure 8 when the door is in its open position.

The keeper 15 is pivoted intermediate its ends and comprises arms 22 and 23, the arm 22 being engaged by a wedge member 25 when the door is in its closed position (see Fig. 7).

The wedge member 25 is slidably journaled in a housing plate 26 fixed to the outer side of the door at its free edge. The housing member 26 is preferably a bent plate which comprises a portion 28 lying flush with the outer side of the door and a portion 29 disposed at right angles to the portion 28. The wedge 25 is disposed in an angle formed by the portions 28 and 29 and is retained in this position by guide members 30 and 31 which are fixed to the portions 28 and 29, respectively.

As best shown in Figures 1 and 6 the wedge, member 25 is provided with a vertically extending slot 35 into which the free end of a lever 36 projects. The lever 36 is fixed to a pin 37 which is rotatably journaled in the housing member 26 and a plate 38, the plate 38 being fixed to the inner side of the door 10. The usual door knob or handles 40 and 41 are fixed to the outer and inner 100

ends, respectively, of the pin 37 and it is readily understood that the door knobs 40 and 41 may be rotated to angularly displace the lever 36 in a clockwise direction (Fig. 1) 5 to lift the wedge member 25. A helical spring 44 yieldingly urges the lever 36 in a counter-clockwise direction (Fig. 1).

Secured to the inner side of the portion 28 is a bracket member 46 which carries a vertically disposed pin 47. Pivoted upon the pin 47 is a member 49 which is yieldingly urged in a clockwise direction (Fig. 2) by a spring 50. The construction is such that when the door is in its closed position, the 15 arm 22 of the keeper 15 projects through a slot 52 formed in the portion 29 of the housing member 26 and holds the member 49 in the position wherein it is shown in Figure 2 so that it does not interfere with downward 20 movement of the wedge member 25. However, when the door 10 is opened, the keeper 15 swings into the position wherein it is shown in Figure 8 and withdraws the arm 22 through the slot 52 so that the spring 50 25 will angularly displace the member 49 into a position wherein it lies against the inner side of the portion 29. This closes the slot 52 and also brings the member 49 into a position wherein it is disposed beneath the wedge 30 member 25 and prevents downward movement thereof.

It may be mentioned at this point in the description that when the door is in its closed position, the wedge 25 urges the arm 23 into engagement with the outer side of the housing portion 29 and engages the arm 22 in the manner illustrated in Figure 3. The weight 35 of the wedge member 25 prevents it from moving upwardly and therefor the wedge 40 member 25 locks the keeper 15 in the position wherein it shows in Figure 2. When the keeper 15 is in this position, the door is held firmly against movement relative to the door frame and any force tending to swing 45 the door on its hinges will only cause the wedge member to drop lower so that the door is held more firmly against movement relative to the door frame.

The lock 10 comprises and is controlled by a 50 tumbler lock which is designated generally by the reference character 55. The tumbler lock 55 comprises a housing 56 which is rigidly secured to the plate 26 (see Figure 4). Surrounding the housing 56 and slidably 55 mounted thereon, is a latch member 57 which comprises an upwardly extending arm 58, provided with a lug 59. The lug 59 functions as a stop member for the lever 36 when the latch member 57 is in the position where- 60 in it is shown in full lines in Figure 4. However, when the latch member 57 is displaced to the right (Figure 4) into the position wherein it is shown in dotted lines, the lug 59 is withdrawn from the path of the lever 36 65 and that lever may be angularly displaced

to lift the wedge member 25. Accidental displacement of the latch member 57 along the housing 56 is prevented by means comprising a ball 60 adapted to engage depressions 61 and 62 formed in the outer surface of the housing 56. The ball 60 is urged into these depressions by a spring 63 carried by the latch member and movable therewith. When the latch member 57 is in the position wherein it is, lug 59 is disposed in the path of the lever 36, the ball 60 engages the depression 61, but when the latch member 57 is moved into the position wherein it is shown in dotted lines in Figure 4, the ball 60 engages the depression 62. It is readily understood, of course, that the spring 63 will yield to permit the latch member 57 to be forced from one of its positions into the other. 70 75 80

It will be noted that the housing member 56 is shaped so that the latch member 57 cannot be angularly displaced around the housing 56. A bar 66 secured to or formed integral with the latch member 57 is provided with a finger piece or knob 68, which is accessible from the inner side of the door 10, 90 the knob 68 being disposed conveniently with respect to the knob 41. 95

A plug 70 is slidably journaled in the housing 56 so that it may be displaced toward or away from the outer side of the door. The 95 plug 70 is held against rotation around its axis by a lug 71 which travels in a slot 72 provided in a housing 56.

A plurality of tumblers 73, slidably mounted in the housing 56 co-operate with a plurality of tumblers 74, slidably mounted in the plug 70 to lock the plug 70 against movement in the housing 56 when the plug is in the position wherein it is shown in full lines 100 in Figure 4. It is readily understood, however, that when a key 75 of suitable conformation is inserted in a keyhole 76 provided in the plug 70 (see Figure 4), the tumblers 73 and 74 will be brought into positions wherein they permit one to push against the key 75 to displace the plug 70 toward the inner side of the door. Such displacement of the plug 70 will displace the bar 66 in the same direction and the bar 66 will, of course, 105 draw the latch member 57 with it so that the lug 59 will be withdrawn from the path of the lever 36. The knob 40 may be manipulated then to cause the lever 36 to lift the wedge member 25. Such displacement of the wedge member 25 unlocks the door 10 so that it may be opened. When the door is opened in this manner, the keeper 15 rotates into the position wherein it is shown in Figure 8, so that the arm 23 will be engaged by the door during its final closing movement. Meanwhile, as long as the door is open, the latch member 25 is held in its upper position by the member 49, against which the wedge member rests. 110 115 120 125

When the door is moved into its closed po- 136

sition, it engages the arm 23 as described above and displaces the keeper 15 so that the arm 22 enters the slot 52 and angularly displaces the member 49 against the action of the 5 spring 50. The wedge 25 then drops into the position wherein it is shown in Figures 3, 5 and 7, so that the door is locked securely against movement relative to the door frame.

The key 75 is provided for use in case one 10 wishes to open the door from the outside thereof. To open the door from the inner side thereof, it is only necessary to pull upon the knob 68 which will operate through the bar 66 to displace the latch member 57 into 15 the position wherein it is shown in dotted lines in Figure 4, whereupon the knob 41 may be manipulated to angularly displace the lever 36 so that it will lift the wedge member 25. The door may be locked at any time by 20 pushing upon the knob 68 so that the plug 70 is displaced into the position wherein it is shown in full lines in Figure 4. When the plug is in this position, and the key 75 is not occupying the keyhole 76, the tumblers 73 and 25 74 lock the plug against movement relative to the housing 56.

As best shown in Figure 4, the tumblers 73 are of different diameters and each tumbler 74 is of the same diameter as its co-operating tumbler 73. The purpose of this construction is to prevent the tumblers 73 from falling into the wrong apertures in the plug 70.

Briefly, the operation of the above described apparatus is substantially as follows: 30 If it is assumed that the door 10 is locked in its closed position, one may unlock the door by inserting the key 75 in the keyhole 76 and then push upon the key 75 to displace the plug 70 and the latch member 57 until the lug 59 clears the lever 36. The knob 40 may then be rotated to have the lever 36 lift the wedge member 25 out of the path of the keeper 15, whereupon the door may be pushed into its open position. Then as one enters through 40 the door, the key 75 may be withdrawn from the keyhole 76, but the lock will remain in its unlocked condition. Then if one wishes to lock the door in its closed position, it is necessary to push upon the knob 68 as described above. The door may be unlocked from the inner side thereof by pulling upon the knob 68. The latter operation does not require the use of the key 75.

Referring now to Figures 9 and 10 where- 50 in another embodiment of the invention is illustrated, the reference character 110 designates generally a lock which has many parts which are identical in construction with similar parts in the lock 12 described above. The lock 110 is particularly adapted for use on clothes-closets or the like and may be operated only from the outer side of the door. In Figures 9 and 10, the parts which are identical in construction with certain parts of the 55 lock illustrated in Figures 1 to 8 inclusive,

are identified by the same reference numerals. Thus, the lock 110 comprises a lever 36, the wedge member 25 and a keeper 15 which function in the same manner as the same parts function in the lock 10. The wedge member 25 is retained in its upper position by a member 49 when the door is opened. In Figures 9 and 10, the door is indicated at 109 and the associated arm is indicated at 111.

The lock 110 comprises and is controlled 70 by a tumbler lock 155 which resembles the lock 55 in construction. The lock 155 comprises a latch member 157 which is slidably mounted upon a housing 156 which is preferably rectangular in cross section. An arm 158 formed integral with latch member 157 is provided with a lug 159 which has the same function as the lug 59 described above. Slidably journaled in the housing 155, is a plug 170 which has tumblers (not shown) adapted 75 to co-operate with the tumblers (not shown) provided in the housing 156. A suitable key may be inserted in the keyhole 176 formed in the plug 170 to bring the tumblers (not shown) into positions wherein they permit displacement of the plug 170 relative to the housing 156. When the key (not shown) has been inserted in this manner, one may pull upon the knob 168 secured to the latch member 157 and the plug 170 to pull the latch member and the plug toward the outer side of the door 110 so that the lug 159 is withdrawn from the path of the lever 36. The lever 36 may then be angularly displaced by manipulating a suitable knob (not shown) provided upon the outer side of the door. The door may be locked by pushing against the knob 168.

Still another form of the invention is illustrated in Figures 11 and 12 wherein I have shown a lock 212, adapted to lock a door 210 to a door frame 211. The lock 212 is identical in construction with the lock 12 described above with the exception that the tumbler lock 55 is replaced by a tumbler lock 255, which controls the operation of the lever 36, which lever has the same function as the lever 36 described above. Similar parts of the locks 12 and 212 are identified by like reference characters.

Tumbler lock 255 comprises a housing member 300 in which a plug 301 is rotatably journaled. Tumblers 304 provided in the plug 301 co-operate with tumblers 305 provided in the housing 300, the construction being such that when a key 306 is withdrawn from a keyhole 307, provided in the plug, the tumblers will prevent rotation of the plug in the housing. Secured to or formed integral with the inner end of the plug 301 is a lever 308 provided with a plug 309 which has the same function as the lugs 59 and 159 described above. When the tumbler lock 255 is in a locked condition, the lever 308 occupies the position wherein it is shown in full 130

lines in Figure 11 so that the lock 309 prevents angular displacement of the associated lever 36 in a clockwise direction (Figure 11). However, if the key 306 is inserted in the key-hole 307, the plug 301 may be angularly displaced to bring the lever 308 into the position wherein it is shown in dotted lines in Figure 11. The lever 36 may then be displaced to have it raise the associated wedge member 25, whereupon the lock 212 will function in the same manner as the lock 12 described above.

It may be mentioned that the lever 36 is fixed to a pin 37 which is identical in construction with the pin 37 described above and is provided with knobs 40 and 41 having the same functions as the knobs 40 and 41 shown in Figure 1.

In the appended claims, the terms "door" and "door frame" are employed in their broadest sense to include closure members and enclosures, respectively, of any description.

While we have shown and described certain embodiments of our invention, it is to be understood that it is capable of many modifications. Changes, therefore, in the construction and arrangement may be made without departing from the spirit and scope of the invention as disclosed in the appended claims, in which it is our intention to claim all novelty inherent in our invention as broadly as possible in view of the prior art.

What I claim as new, and desire to secure by Letters Patent, is:

1. A lock for a door mounted in a door frame, which lock comprises a keeper member pivotally mounted on the door frame, a wedge member carried by the door and movable vertically to engage said keeper member to lock the door in its closed position, and means for disengaging said wedge member from said keeper member to unlock the door.

2. A lock for a door mounted in a door frame, which lock comprises a keeper member pivoted on the frame, a spring for yieldingly urging said keeper member into a predetermined position, a wedge member carried by the door and movable vertically to engage said keeper member to lock the door in its closed position, and means for disengaging said wedge member from said keeper member to unlock the door.

3. A lock for a door mounted in a door frame, which lock comprises a keeper member movably mounted on a door frame, a wedge member carried by the door and movable into a position wherein it engages the keeper member to lock the door in its closed position, means carried by the door for holding said wedge member in a retracted position, and means for disengaging said wedge member from said keeper member to unlock the door.

4. A lock for a door mounted in a door frame, which lock comprises a keeper member movably mounted on a door frame, a wedge member carried by the door and movable into a position wherein it engages said keeper member to lock the door in its closed position, means carried by the door and adapted to hold the wedge member in a retracted position, said means being adapted to be displaced by said keeper member so that said wedge member may move out of its retracted position, and means for disengaging said wedge member from said keeper member to unlock the door.

5. A lock for a door mounted in a door frame, which lock comprises a keeper member, said keeper member being pivoted to said door frame and being provided with two arms, one of said arms being engaged by said door when it is moved into its closed position and the other of said arms being adapted to move into the path of said door when the first arm is displaced by the door, a wedge member slidably mounted in the door and adapted to engage the arm which moves into the path of the door, the last mentioned arm and said wedge member co-operating to lock the door in its closed position, and means for disengaging said wedge from the last mentioned arm to unlock the door.

6. A lock for a door mounted in a door frame, which lock comprises a two-armed keeper member pivoted to said door frame, a spring yieldingly urging said keeper member into a predetermined position, a wedge member carried by the door and engageable with one of the arms of the keeper member for locking the door in its closed position, the other arm of said keeper member being adapted to engage the free edge of said door when the door is in its closed position, means carried by the door for holding the wedge member in a retracted position, said means being adapted to be displaced by said keeper member when said door is moved into its closed position, and means carried by the door for disengaging said wedge member from said keeper member.

7. A lock for a door mounted in a door frame which lock comprises a two-armed keeper member pivoted to said door frame, a spring yieldingly urging said keeper member into a predetermined position, a wedge member carried by the door and engageable with one of the arms of the keeper member for locking the door in its closed position, the other arm of said keeper member being adapted to engage the free edge of said door when the door is in its closed position, pivoted means carried by the door for holding the wedge member in a retracted position, said means being adapted to be displaced by said keeper member when said door is moved into its closed position, and means carried

by the door for disengaging said wedge member from said keeper member.

8. A lock for a door mounted in a door frame, which lock comprises a keeper member movably mounted on a door frame, a wedge member carried by the door and engageable with said keeper member to lock the door in its closed position, a pin journaled in the door, a knob on said pin whereby said pin may be rotated, a lever carried by said pin and engaging said wedge, and an auxiliary lock controlling said lever.

9. A lock for a door mounted in a door frame which lock comprises a keeper member movably mounted on a door frame, a wedge member carried by the door and engageable with said keeper member to lock the door in its closed position, means including a pivoted lever for disengaging said wedge member from said keeper member to unlock the door, a stop adapted to prevent angular displacement of said lever, said stop being movable transversely of said lever into a position wherein it permits angular displacement of said lever and an auxiliary lock for controlling said stop.

10. A lock for a door mounted in a door frame, which lock comprises a keeper member movably mounted on a door frame, a wedge member carried by the door and engageable with said keeper member to lock the door in its closed position, means including a pivoted lever for disengaging said wedge member from said keeper member to unlock the door, a stop for preventing angular displacement of said lever, said stop being mounted for movement parallel to the path in which said pivoted lever travels, and an auxiliary lock for controlling said stop.

40 11. A lock for a door mounted in a door frame, which lock comprises a two-arm keeper member pivoted to said door frame in overlapping position, said door being provided with a slot adapted to be entered by an arm 45 of said keeper member, a wedge member carried by the door and engageable with said arm in the slot when the door is in its closed position, and means carried by the door for disengaging said wedge member from said keeper member.

In testimony whereof, I have hereunto affixed my signature, this 27th day of June, 1931.

OSCAR RITTERBUSCH.
